UNITED STATES PATENT OFFICE.

EDWIN E. BARNEY, OF ILION, NEW YORK, ASSIGNOR TO REMINGTON TYPEWRITER COMPANY, OF ILION, NEW YORK, A CORPORATION OF NEW YORK.

TYPE-WRITING MACHINE.

1,125,922.

Specification of Letters Patent. Patented Jan. 26, 1915.

Application filed July 12, 1913. Serial No. 779,692.

To all whom it may concern:

Be it known that I, EDWIN E. BARNEY, a citizen of the United States, and resident of Ilion, in the county of Herkimer and State of New York, have invented certain new and useful Improvements in Type-Writing Machines, of which the following is a specification.

My invention relates to typewriting machines and also to other machines in which paper is used after the fashion of typewriting machines, such, for example, as some forms of adding machines.

My invention has for its principal object to provide improved paper feed mechanism for such machines.

One of the objects had in mind in the present invention has been to provide paper feed mechanism of inexpensive construction and yet thoroughly good and efficient.

To the above and other ends my invention consists in certain features of construction and combinations and arrangements of parts, all of which will be fully set forth herein and particularly pointed out in the claims.

In the accompanying drawings, Figures 1 and 2 are vertical fore and aft sectional views through the carriage of a typewriting machine, with my invention embodied therein, both of said figures being on an enlarged scale. In Fig. 1 the parts are shown in normal positions and in Fig. 2 in releasing positions. Fig. 3 is a front elevation, and Fig. 4 is a top plan view of said carriage.

In the drawings parts have been omitted and parts have been shown in section or broken away as found convenient.

As far as my present invention is concerned the typewriting or other machine can, as to most of its features, be of any suitable sort. In the present instance I have shown in Fig. 1 part of a stationary rail 1, which rail has its forward and rear edges grooved to coöperate with antifriction balls 2, which in turn support grooved rails 3 constituting part of a typewriter carriage having end pieces or brackets 4. Stationary and movable rail construction and the ball bearings therefor, such as are sought to be represented in the present case, are more fully shown in the patent to Alexander T. Brown No. 935,776, dated October 5, 1909, although it will of course be under-

stood that as far as my invention is concerned these parts may be otherwise constructed, and indeed it is not essential to my invention that the parts hereinafter described be on a carriage at all. Said carriage as here shown, constitutes a platen frame in which a cylindrical platen 5 is mounted by means of its axle 6, which axle is journaled in the end brackets 4. Said platen may be provided with the usual finger wheels or other suitable means for turning it, and it is here shown equipped with a line space wheel 7 to be operated by any suitable pawl or other mechanism after the ordinary fashion of these machines. In the particular machine shown in the drawings, type bars 8 (Fig. 1) are so mounted as to strike against the front face of the platen 5, as shown.

In the platen frame above described, I pivot a yoke frame comprising a left-hand arm 10, a right-hand arm 11 and a cross rod or bar 12 connecting the upper parts of said arms 10 and 11 below and in front of the center of the platen. Each of the arms 10 and 11 is provided at its lower end with a stud or trunnion 13 suitably pivoted in the end brackets 4, as indicated in Figs. 1 and 3. The rod 12 is rigidly secured at its ends to the arms 10 and 11 so that when one of said arms turns about its pivot 13 the other arm is caused to turn also.

A scale plate 14 is shown situated at a suitable distance below the front face of the platen 5, said scale plate consisting of a strip of metal having its ends secured by screws 15 to ears 16 bent off from the arms 10 and 11.

It will be perceived that the rod 12 is so mounted that when the yoke frame of which it forms a part is rocked about its pivots 13, said bar moves forward and somewhat downward.

A paper apron or deflector 17 extends longitudinally of the platen and is formed concave on its upper surface and is so disposed that normally its forward part is pressed against the platen, as shown in Fig. 1. At each of its ends this paper apron has bent off therefrom an ear 18 which is formed with an open slot that straddles the end of the rod 12 to which the paper apron is thereby detachably pivoted. As shown in Fig. 3 these ears come just inside the arms 10 and 11. At its rear edge and at each

and thereto said paper apron has connected thereto the forward end of a contractile spring 20, which spring at its rear end is connected to a cross frame bar 21 which is secured by screws 22 to the rear edges of the brackets 4. It will be seen that the tension of the springs 20 is exerted to pull the rod 12 toward the rear of the machine, thus turning the yoke frame about its pivots 13 and that said yoke frame so guides the forward part of the paper apron as to press said forward part with spring pressure against the lower front surface of the platen, the forward edge of said paper apron coming at 26 a suitable distance below the writing line, the location of which can be understood from Fig. 1. Preferably the springs 20 constitute the sole support for the rear edge of the paper apron. In order to release the paper a paper feed release handle or lever 23 is provided, said lever consisting of a suitable piece of sheet metal pivoted on a pivot screw 24, here shown as screwed into the inside face of the left-hand bracket 4. The lever 23 normally stands in the position shown in Fig. 1 and below its pivot it has a flange 25 (Figs. 2 and 3) bent off therefrom toward the left, said flange being preferably formed in a curve substantially concentric with the pivot 24. An arm 26 constituting an integral part of the arm 10, extends backward from the rod 12 nearly to a point just in front of said flange 25. The construction is such that when the lever 23 is pushed back to the position shown in Fig. 2 the flange 25 lifts the arm 26, which arm then runs on to the concentric part of the flange as shown. This operation tilts the yoke frame 10, 11, 12 about its pivots 13, moving the rod 12 forward and downward and said rod drawing with it the paper apron 17 against the tension of the springs 20, all as will be understood from Fig. 2. When the parts stand as shown in Fig. 2 the pressure of the arm 26 comes against the concentric part of the flange 25 and therefore has no tendency to restore the lever 23 to normal position, but when said lever is nearly restored to normal position and the end of the arm 26 comes against the end of the flange 25, then said springs do tend to restore said lever fully to normal position.

A paper apron controlled by two springs 20 situated in much the same position as the springs 20 and said paper apron having about the same fore and aft motion as my paper apron 17, was constructed by Arthur W. Smith prior to my invention and such combination is, therefore, not claimed in this application. The particular means shown and described for guiding said paper apron and for moving it to releasing position are of my invention, however, and are claimed herein.

I have provided paper fingers or marginal paper guides of novel and improved construction and arrangement. Each of these comprises an upper arm 27, which for part of its length has substantially the curvature of the platen against which it is adapted to press the paper; but, as shown in Fig. 1, the lower part of said arm 27 is suitably bent away from the platen to avoid the paper apron 17. Each of my paper fingers 28 also comprises a lower arm 28, which is made of suitable size, shape and material to act as a flat spring. Each of said paper fingers also includes two transverse arms or branches 30, each at its end prolonged downward and curved part way around the rear and underside of the rod 12 to form a sort of hook 31 that embraces said rod to a sufficient extent so that the paper finger as a whole is pivoted on said rod. Preferably, however, this hook does not extend much if any more than half way around the rod so that the paper finger is readily detachable by simply forcing it downward and to the rear enough to disconnect it from the rod. The lower end of the arm 28 bears against any suitable part of the framework and it is here shown as bearing against the forward surface of the forward rail or carriage bar 3. By an inspection of Fig. 1 it will be seen that each of these paper fingers is in the nature of a lever of the first order pivoted at its middle on the rod 12 and bearing at its lower end against the rail 3, and at its upper end against the platen. These paper fingers can be adjusted lengthwise of the platen by sliding them along the rod 12 and they will be retained in their adjusted positions by friction due to the resilience of the parts. Preferably each paper finger consists of a single integral piece of resilient sheet metal stamped out in the proper form and bent up as shown. It will be perceived that these paper fingers are of extreme simplicity and that they are inexpensive to manufacture. They are, however, thoroughly good paper fingers and answer their purpose satisfactorily. Since these paper fingers are pivoted on the rod 12, it will be perceived that they move to 115 releasing position where their pressure is relaxed when said rod 12 is moved forward by the operation of the release lever 23, as shown in Fig. 2.

I have provided suitable main feed rollers 32, the number of which can be varied, two being shown in the present instance. These are here shown in alignment with each other and situated in about the usual location, at the rear and below the center of the platen. Each of said rollers has an axle 33 suitably supported. In the present instance, and preferably, said axle is formed near each of its ends with a peripheral groove and a hanger arm 34 is formed at its free end with 130

an open ended slot, as shown in Figs. 1 and 2, said slot being of a width appropriate to the diameter of the axle at the bottom of said groove so that said axle is journaled in said slotted arm and motion of the axle lengthwise is prevented. The hanger arm 34 constitutes part of a hanger, the upper rear part of which comprises two ears 35 connected together by a yoke bar 36, the arm 34 consisting of a prolongation of one of said ears. The whole hanger is preferably made of sheet metal punched out and bent into the form shown. Each of the ears 35 is perforated and pivoted on a transverse rock shaft 37 which at its ends is journaled in the brackets 4. A wire spring 38 is formed at its middle with a loop that is hooked under some stationary part. In the present instance said loop is hooked under an ear 40 bent off from an upstanding arm of the cross bar 21. Each of the two branches of this looped spring is coiled several times around the shaft 37 between the two ears 35 and each of the free ends of the spring is hooked under the yoke bar 36, as is apparent from the drawings. It will be seen that the tension of this spring is exerted to turn the hanger about the shaft 37 and to press the roll 32 against the platen. It will also be perceived that the springs 38 do not get their turning moment from the shaft 37 but that said springs are connected at one end to the hangers and at the other end to a fixed part independent of said shaft. It will also be perceived that the two ends of each roller are separately and independently sprung pressed toward the platen. Each of the yoke bars 36 is formed with a hole 41, Fig. 2, through which passes a pin, here shown as consisting of a screw 42 with an elongated head and screwed into the shaft 37. This pin or screw is smaller in diameter than the hole 41 so that the hanger has a limited amount of pivotal movement on the shaft 37 independent of the pin and enough to allow to each hanger a sufficient degree of independent motion. These pins also locate the several hangers lengthwise of the shaft 37. It will be perceived that, in assembling the parts, the hangers can be strung along the shaft by inserting said shaft through the ears 35 and through the springs 38, and that the screws 42 can be put in place afterward. In order to release the paper it is necessary to move the roll or rolls 32 away from the platen, and this is done in the present instance by rotating the shaft 37 toward the front of the machine. The pins 42, acting against the forward edges of the holes 41, cause the rolls 32 to be moved away from the platen as shown in Fig. 2. In order to rock the shaft 37 for this purpose said shaft has on its left-hand end an arm 43, the forward end of which constitutes a sort of a nose that lies beneath a part of the release lever 23, as shown in Fig. 1. Said lever is formed with a cam part 44 and a dwell 45. The construction is such that when the lever is pushed back to the releasing position shown in Fig. 2, said cam part 44 depresses the arm 43 and rocks the shaft 37, carrying with it the several hangers, each against the tension of its spring 38. When the lever is in the position shown in Fig. 2 the arm 43 is resting against the dwell 45 so that the tension of said springs does not restore the lever 23 to normal position; but when said lever is restored toward normal position by hand, in the latter part of its motion the arm 43, acting on the cam 44, tends to restore the lever fully. It will be seen, therefore, that the main feed rolls are thrown off by the same release lever 23 which also acts on the paper apron and on the paper fingers.

I prefer to construct the feed rolls 32 in a manner that will be understood by reference to Fig. 4 where the right-hand one of the two rolls shown is represented in longitudinal section. This roll comprises a core 46 consisting of a piece of metallic tubing, the internal diameter of which is greater than the external diameter of the axle 33. Tubing of this sort and of suitable material is an ordinary and comparatively inexpensive article of commerce. This tubing is cut of suitable length and its ends contracted in any suitable way, as by drawing or spinning until they are of a size adapted to be journaled on the axle 33, as shown in Fig. 4. This gives ample clearance between the core 46 and the axle 33 throughout all of the length of said core and axle except at the ends where there is a good bearing. The full-size part of the core is covered with any suitable covering 47, as, for example, a covering of rubber. This entire roll construction, including the cover 47, core 46, axle 33, and the manner of mounting said axle in the hangers, is of inexpensive but very good mechanical construction. It will be perceived that the roll can be disassembled by lifting the axle out of the slots in the hanger arms 34 and slipping said axle lengthwise out of the core.

I have provided a paper table 50 which may be of usual or any suitable outline and so located as to perform the usual functions of this part of the machine. Said paper table has two arms 51 depending therefrom and each preferably consisting of a strip of sheet metal riveted or otherwise fastened to the back of the paper table. These arms 51 are detachably secured to the cross bar 21 in a novel manner. Said cross bar has two upright arms 52 each of which has a part 53 folded back upon itself so as to leave a vertical slot between the upright arm and this folded part, into which slot one of the arms 51 is inserted from the top. It will of course

be understood that the arm 52 can be made straight, if preferred, and the fold be in the arm 51.

The cross frame bar 21 preferably consists of a strip of sheet metal stamped out in appropriate form and having a flange 54 bent off therefrom along its bottom edge in order to stiffen it. This flange extends approximately to the inner faces of the brackets 4 and the vertical part of the bar extends far enough farther to be fastened by the screws 22 to the rear edges of the brackets. This bar, in addition to strengthening the general construction of the carriage, serves as a support for the paper table and for the springs 20 and 38 and in the actual machine from which these drawings were made, it serves other purposes also. In order to stiffen the construction I preferably, near the middle of the machine, provide an upright part 55 to this bar, which in the present instance is shown as a continuation of one of the ears 35. Part of this upright is bent toward the front of the machine to form a bracket 56, Figs. 1 and 4, which bracket lies beneath the shaft 37 and has a semi-circular cut-out therein in which said shaft fits. This bracket stiffens the shaft against the pressure of the several springs 28 and the shaft itself is of some assistance in stiffening the bar 21 in a front and back direction. In short, these bars are stiffer for being thus connected together.

It will of course be understood that the machine can be provided with only one main feed roller 32 or with several, depending upon the length that it is preferred to make these rollers and also upon the length of the platen, the character of the construction being flexible in this regard. It will also be understood that various other changes can be made in the details of construction without departing from the spirit of my invention.

What I claim as new and desire to secure by Letters Patent, is:—

1. The combination of a platen, a platen frame, a yoke frame comprising a transverse rod and two arms, said arms pivoted in said platen frame, a paper apron pivoted to said yoke frame, and spring means acting directly on said paper apron and acting through said paper apron on said yoke frame.
2. The combination of a platen, a platen frame, a yoke frame comprising a transverse rod and two arms, said arms pivoted in said platen frame, a paper apron pivoted to said yoke frame so as to move in a forward and downward direction when said frame is moved, and springs acting on said paper apron and tending to draw said paper apron toward the rear, and said paper apron, acting under the impulse of said springs, tending to move said rod upward and backward.

3. The combination of a platen, a platen frame, a frame pivoted to said platen frame, a paper apron supported at its forward part on said pivoted frame, and springs constituting the sole support for the rear part of said paper apron.

4. The combination of a platen, a platen frame, a yoke frame comprising a transverse rod and two arms, said arms pivoted in said platen frame, a paper apron pivoted to said yoke frame so as to move in a forward and downward direction when said frame is moved, springs tending to draw said paper apron toward the rear, and paper feed release devices including means for rocking said frame toward the front of the machine.

5. The combination of a platen, a platen frame, a frame pivoted to said platen frame, a paper apron supported at its forward part on said pivoted frame, springs constituting the sole support for the rear part of said paper apron, and paper feed release devices including means acting on said frame to rock it toward the front of the machine against the tension of said springs.

6. The combination of a platen, a platen frame, a yoke frame comprising a transverse rod and two arms, said arms pivoted in said platen frame, a paper apron pivoted to said yoke frame so as to move in a forward and downward direction when said frame is moved, springs tending to draw said paper apron toward the rear, and one or more paper fingers mounted on said rod.

7. The combination of a platen, a platen frame, a yoke frame comprising two arms each pivoted at its lower end, a transverse rod connecting said arms, paper fingers mounted on and adjustable along said rod, spring means tending to draw said rod toward the rear, and paper feed release mechanism adapted to move said rod toward the front.

8. The combination of a platen, a platen frame, a yoke frame pivoted in said platen frame and comprising two arms each pivoted at its lower end to said platen frame, a cross rod connecting said arms, paper fingers on said cross rod, and a scale plate also connecting said arms.

9. The combination of a platen, a platen frame, a frame pivoted in said platen frame and comprising a cross rod having freedom to move in a front and back direction, a paper finger mounted on said rod and having an arm extending up in front of said platen and an arm extending downward whereby said paper finger has the general form of a lever of the first order pivoted on said rod, the lower arm of said lever pressing against a part of said platen frame to put the paper finger under spring tension against the platen.

10. The combination of a platen, a platen frame, a frame pivoted in said platen frame

and comprising a cross rod having freedom to move in a front and back direction, a paper finger mounted on said rod and having an arm extending up in front of said platen 5 and an arm extending downward whereby said paper finger has the general form of a lever of the first order pivoted on said rod, the lower arm of said lever pressing against a part of said platen frame to put the paper 10 finger under spring tension against the platen, and means for moving said rod toward the front to release the pressure on said paper finger and to move said rod toward the rear to put said paper finger under tension.

11. The combination of a platen, a platen frame, a frame pivoted in said platen frame and comprising a cross rod having freedom to move in a front and back direction, a paper finger mounted on said rod and having an arm extending up in front of said platen and an arm extending downward, whereby said paper finger has the general form of a lever of the first order pivoted on said rod, the lower arm of said lever pressing against a part of said platen frame to put the paper finger under spring tension against the platen, and spring means for drawing said rod toward the rear to put said paper finger under tension against the platen.

12. The combination of a platen, a platen frame, a frame pivoted in said platen frame and comprising a cross rod having freedom to move in a front and back direction, a paper finger mounted on said rod and having an arm extending up in front of said platen and an arm extending downward, whereby said paper finger has the general form of a lever of the first order pivoted on said rod, the lower arm of said lever pressing against a part of said platen frame to put the paper finger under spring tension against the platen, spring means for drawing said rod toward the rear to put said paper finger under tension against the platen, and paper feed release devices for moving said rod toward the front.

13. The combination of a platen, a platen frame, a frame pivoted in said platen frame and comprising a cross rod having freedom to move in a front and back direction, a paper finger mounted on said rod and having an arm extending up in front of said platen and an arm extending downward, whereby said paper finger has the general form of a lever of the first order pivoted on said rod, the lower arm of said lever pressing against a part of said platen frame to put the paper finger under spring tension against the platen, a paper apron pivoted on said rod, and spring means for drawing said apron and rod toward the rear to press said paper apron and said paper finger against the platen.

14. The combination of a transverse rock

shaft, pins projecting from said shaft, a plurality of pairs of hangers, each hanger pivoted on said shaft and having lost motion connection with one of said pins, springs acting between said hangers and a relatively fixed part of the machine, feed rollers journaled in said pairs of hangers, a platen against which said feed rollers are pressed by said springs, and means for rocking said shaft to move said rollers away from said platen.

15. The combination of a platen, a rock shaft, a plurality of pairs of hangers, each hanger pivoted on said rock shaft, feed rollers journaled in said pairs of hangers, springs connecting said hangers with a fixed part and acting independently on the several hangers to press the feed rollers against the platen, pins having loose or lost motion connection with the several hangers, said pins serving to prevent motion of said hangers longitudinally of said shaft and serving also to communicate motion to said hangers when said shaft is rocked and normally leaving the hangers with freedom for independent movement, and means for rocking said shaft to release the feed rollers.

16. The combination of a platen, a rock shaft, sheet metal hangers each comprising an arm and a yoke having two ears bent off from said yoke and journaled on said rock shaft; feed rollers journaled in said arms; pins projecting from said shaft through holes in said yokes a little larger than the pins; springs acting on said hangers independently of one another and means for rocking said shaft.

17. The combination with a feed roller, of a hanger for said feed roller comprising a yoke bar and two ears; a shaft on which said ears are pivoted; a spring looped in the middle and having two coils surrounding said shaft, the free ends of said spring acting on said yoke bar; and a fixed projection under which said loop is caught.

18. The combination with a shaft and a feed roller, of a hanger for said feed roller comprising a yoke bar parallel with said shaft and two ears bent off from said yoke bar and pivoted on said shaft, a spring acting on said hanger, a pin projecting from said shaft through a hole in said yoke bar larger than said pin, whereby said pin locates said hanger lengthwise of said shaft and allows to said hanger a limited amount of independent pivotal motion on said shaft, and means for rocking said shaft.

19. The combination with a feed roller, of a hanger for said feed roller comprising a yoke bar and two ears; a shaft on which said ears are pivoted; a spring looped in the middle and having two coils surrounding said shaft, the free ends of said spring acting on said yoke bar; a fixed projection under which said loop is caught; a pin pro-

jecting from said shaft through a hole in said yoke bar larger than said pin; and means for rocking said shaft.

20. The combination of an axle, and a
5 roller journaled on said axle and made of
a piece of tubing having an internal di-
ameter greater than the external diameter
of said axle and said piece of tubing itself
having its ends narrowed down to take a
10 bearing on said axle, and a covering for said
tubing.

21. The combination of an axle having peripheral grooves at its ends, hanger arms having notches engaging said grooves, and
15 a roller journaled on said axle and comprising a metal tube whose internal diameter is greater than the external diameter of said axle and the ends of said tube itself being narrowed down to take a bearing on said
20 axle, and a softer covering for said tube.

22. The combination of a platen, a platen frame, a pivoted yoke frame carrying paper feed devices and having a rearwardly extending arm, a rock shaft, feed roll hangers connected thereto, a crank arm connected to said rock shaft, and a release key having

a cam to act on said crank case for rocking said shaft said feed roll hangers and having also a second cam for acting on the rearwardly extending arm of said rock frame.

23. The combination of a platen, a platen frame, a yoke frame pivotally mounted therein and comprising a transverse rod, a paper apron pivotally supported at its forward portion upon said rod, springs 25 supporting the rear portion of said apron and having a rearward pull thereon, paper fingers supported by said transverse rod, a rock shaft, feed roll hangers connected thereto, springs connected to said hangers, a crank arm on said rock shaft, a crank arm on said yoke frame, and a release key provided with means for operating upon both said crank arms.

Signed at Bronx, in the county of Bronx,
and State of New York, this 15th day
of July, A. D. 1918.
